UNITED STATES PATENT OFFICE

143,413

DESIGN FOR A CHEST OR SIMILAR ARTICLE

Signa N. Erickson, Pasadena, Calif.

Application April 5, 1945, Serial No. 118,861

Term of patent 14 years

(CL D33—19)

To all whom it may concern:

Be it known that I, Signa N. Erickson, a citizen of the United States, residing at Pasadena, in the county of Los Angeles and State of California, have invented a new, original, and ornamental Design for a Chest or Similar Article, of which the following is a specification, reference being had to the accompanying drawings, forming a part thereof.

Referring to the drawings:

Figure 4 is a perspective view showing the side and front as it appears with the parts in open position.

The rear panel of the chest is substantially plain and unornamented.

I claim:

The ornamental design for a chest or similar article, substantially as shown and described.

SIGNA N. ERICKSON.
